UNITED STATES PATENT OFFICE.

EDWIN B. PLUMB, OF CLAWSON, MICHIGAN.

BEDCLOTHES-HOLDING DEVICE.

1,373,670.

Specification of Letters Patent.

Patented Apr. 5, 1921.

Application filed October 6, 1919. Serial No. 328,804.

To all whom it may concern:

Be it known that I, EDWIN B. PLUMB, a citizen of the United States of America, residing at Clawson, in the county of Oakland 5 and State of Michigan, have invented certain new and useful Improvements in Bed-clothes-Holding Devices, of which the following is a specification, reference being had therein to the accompanying drawings.

10 This invention relates to a bed clothes holding device and the object of my invention is to provide a simple, durable and inexpensive device that may be easily and quickly installed on a bed, crib, or other 15 structure for retaining clothes thereon, so that the same cannot become accidentally displaced during the slumber of a restless child, or one that tosses or repeatedly moves in the bed or crib, it being a well known 20 fact that restless children become uncovered during the night and are more or less exposed, thus requiring the attention of others. With my device the edges of the clothes are yieldably held so that a child may 25 turn or move and sleep in comfort without undue pressure of the clothes on the body, and at the same time be assured of bodily cover. The device is designed so as not to injure the bed clothes and when not in use 30 to occupy a comparatively small space.

The details of construction entering into my invention will be hereinafter considered and then claimed, and reference will now be had to the drawing, wherein,

35 Figure 1 is a plan of a bed provided with a clothes holding device in accordance with my invention;

40 Fig. 2 is an enlarged cross sectional view of the clamp forming part of the device, and Fig. 3 is an enlarged side elevation of a portion of the device.

The clothes holding device comprises two parallel flexible members 1 that may be made of rope, wire, or any material suitable for 45 the purpose, and the ends of said members are tied or otherwise attached, as at 2, to coiled retractile springs 3 having end convolutions thereof terminating in hooks 4 provided with covers 5 that may be made of 50 rubber tubing. The hooks 4 are adapted to be placed in engagement with the head and foot pieces 6 of a bed along the longitudinal edges thereof and the members 1 are maintained taut by the springs 3. At certain 55 ends of the members 1 there may be take-up devices 2^a which will permit of the tension

of the springs 3 being increased or decreased after being installed.

Mounted on the members 1, at suitable intervals, are two part clamps, each composed 60 of oblong sections 7 having flat confronting faces 8 with a face of one of said members provided with a longitudinal groove 9 to receive the members 1. The groove 9 is adjacent one end of the clamp and the member 1, 65 after having bed clothes placed in engagement therewith, is compressed between the sections 7.

One of the clamp sections 7 is provided with a screw bolt 12 extending through an 70 opening 13 in the other clamp section and provided with a winged thumb-nut 14 so that the clamp section 7 may be locked together on the member 1 and the clothes 11. The clothes 11 may be gripped at points 75 inset from the sides of the end thus not interfere with the tucking in of the bed clothes, and while it is preferable to use two devices one at each side of the bed, as shown, I may use three, or even more. One or two of the 80 devices may be released relative to the bed clothes so that a child may be placed in bed and then with all of the devices in operative relation the bed clothes will be yieldably 85 held without any danger of accidental displacement due to any movement of the occupant of the bed.

The clamps may be made of wood or suitable material finished to harmonize with the bed and when the bed is to be made up the 90 entire device may be removed if necessary.

One embodiment of my invention has been illustrated but it is to be understood that the structural elements are susceptible to such variations and modifications as fall 95 within the scope of the appended claims.

What I claim is:—

1. A bed clothes holding device comprising 100 flexible members disposed in parallelism and adapted to have the ends thereof connected to the ends of a bed so as to extend lengthwise thereof at the side edges of the bedclothes, and detachable clamps at intervals on said flexible members and adapted to frictionally grip the side edges of the bed 105 clothes.

2. A bed clothes holding device comprising 110 parallel flexible members, coiled retractile springs at the ends thereof terminating in hooks adapted for engagement with the ends of a bed and support said flexible members lengthwise thereof at the side edges of

the bedclothes, covers on the hooks of said springs, and detachable clamping devices at intervals on said flexible members and adapted to frictionally engage bed clothes adjacent said flexible members without interfering with the tucking in of the bed clothes.

3. A bed clothes holding device comprising members adapted to have the ends thereof connected to the ends of a bed and extend lengthwise thereof, said members being mov-

able relative to the clothes of the bed and to and from each end of the bed, and means adapted to connect said members to the bed clothes of the bed.

In testimony whereof I affix my signature 15 in the presence of two witnesses.

EDWIN B. PLUMB.
